(57) **CLAIM**

The ornamental design for a pneumatic tire, as shown and described.

DESCRIPTION

FIG. 1 is a perspective view of a pneumatic tire showing our new design, it being understood that the tread pattern repeats throughout the entire outer circumference;

FIG. 2 is an end elevation view thereof;

FIG. 3 is a partial end view thereof, shown at an enlarged scale;

FIG. 4 is an opposite end elevation view thereof;

FIG. 5 a side elevation view thereof; and,

FIG. 6 is an opposite side elevation view thereof.

The broken lines along the top and bottom edges of FIG. 3 show the boundaries of the figure and form no part of the claimed design. All other broken lines in the drawings depict environmental subject matter only and form no part of the claimed design.
